UNITED STATES PATENT OFFICE

2,109,023

CLOTHESPIN

Daniel W. Hilderbrant, Farmersville, Calif.

Application March 4, 1937, Serial No. 129,039

1 Claim. (Cl. 24—139)

This invention relates to improvements in metal clothespins.

An object of the invention is to provide a clothespin composed of a single strand of wire, that can be economically made and which will function more satisfactorily than clothespins now in commercial use.

A further object of the invention is to provide a device that can be quickly and easily attached or removed from the line without being frictionally engaged or disengaged.

Other objects and advantages of the invention will become apparent from the description and drawing, wherein:—

15 Figure 1 is a front elevational view of the device applied to a clothesline;

Figure 2 is a view similar to Figure 1, except that the legs have been compressed to permit the clothesline being engaged or disengaged.

20 Figure 3 is an edge view in elevation;

Figure 4 is a sectional view taken on the line 4—4 of Figure 1, and

Figure 5 is a fragmentary sectional view taken on the line 5—5 of Figure 1.

25 Referring more particularly to the drawing wherein like reference characters designate like or corresponding parts in the different views, 10 designates a strand of wire which is shaped to form the clothespin. The strand 10 is provided 30 with a plurality of loops intermediate of the ends forming coils 11 and 12. The end portions 13 and 14 extend tangentially from the ends of coils 11 and 12 and incline slightly toward each other. The portion 13 is bent at 15 and extended towards and beyond the end portion 14 and there bent at 15^a to form a loop having parallel sides 16 and 17 providing a guide loop for end portion 14 as best shown in Figure 4. The side portion 17 is then bent towards side portion 16 and downwardly as shown at 17^b, then under portion 16 at 17^b and upwardly at 17, then bent into a hook, 18^a having its terminal ending adjacent side 17 providing a guide loop as best shown in Figure 5.

40 The member 14 extends up between the sides 16 and 17 and is then bent approximately at right angles at 19 to form the portion 20 which extends through and is guided by the loop 18,

18^a as also best shown in Figure 5. The portion 20 is bent downwardly and inwardly at 21 and the end is returned on itself and formed into a notch portion 22 which normally rests close to the member 13.

5 Members 13 and 14 are squeezed toward one another against the resilience of spring coils 11 and 12. The member 14 will slide in the guide-way formed by the portions 16 and 17 and this movement will cause part 22 to move away from part 13 sufficiently to allow a clothesline 23 to pass between parts 13 and 22, as seen in Figure 2. The parts 13 and 14 are then released and the device assumes its normal position with the clothesline resting in the recess between part 15 21 and part 15, as seen in Figure 1.

The material to be suspended can either be engaged between the coils 11 and 12 or be hung over the line 23 and will be securely held in either position. To disengage the device, members 13 20 and 14 are pushed together and the device lifted off of line 23.

25 It is to be understood that only the preferred embodiment of the invention has been illustrated, the right being reserved to make such changes and modifications as will not depart from the spirit and scope of the invention.

I claim as my invention:—

30 In a clothespin formed of a single strand of resilient wire, a coil intermediate the ends thereof, two substantially parallel legs extending from opposite ends of said coil, a substantially right angled portion extending from the end of one leg toward and beyond the other leg, said substantially right angled portion having at its end 35 a return bend extending toward the coil forming a hook element, said second mentioned leg having at its end a guide comprising two loops, one enclosing and normal to the first mentioned leg, the other enclosing and normal to the substantially right angled portion, said hook element 40 and said second leg cooperating to form a recess whereby a clothesline and clothes suspended thereon may be secured and retained, the clothes normally extending downward in a direction 45 parallel to said second leg.

DANIEL W. HILDERBRANT.
